(57) **CLAIM**

The ornamental design for a rotor assembly for use in an earplug dispenser, as shown and described.

DESCRIPTION

FIG. 1 is a top perspective view of a rotor assembly for use in an earplug dispenser, according to my design;

FIG. 2 is a bottom perspective view thereof;

FIG. 3 is a front view thereof;

FIG. 4 is a right side elevational view thereof;

FIG. 5 is a rear side elevational view thereof;

FIG. 6 is a top plan view thereof; and,

FIG. 7 is a bottom plan view thereof.

The broken lines in the drawings depict portions of the rotor assembly for use in an earplug dispenser that form no part of the claimed design.

1 Claim, 5 Drawing Sheets
